UNITED STATES PATENT OFFICE

97,889

DESIGN FOR A MOLDED JELLY OR SIMILAR FOOD PRODUCT

Marie Baker, Salem, Oreg.

Application September 3, 1935, Serial No. 58,418

Term of patent 14 years

To all whom it may concern:

Be it known that I, Marie Baker, a citizen of the United States, residing at Salem, county of Marion, and State of Oregon, have invented a new, original, and ornamental Design for a Molded Jelly or Similar Food Product, of which the following is a specification, reference being had to the accompanying drawing, forming a part thereof.

In the drawing:

Fig. 1 is a top view in perspective of a molded jelly or similar food product, showing my new design;

Fig. 2 is a top or plan view of the same;

Fig. 3 is a side elevation;

Fig. 4 is a side view, slightly in perspective, of the molded article turned as in Fig. 1; and

Fig. 5 is a bottom plan view.

I claim:

The ornamental design for a molded jelly or similar food product, substantially as shown.

MARIE BAKER.
